CLAIM

The ornamental design for a bottle, as shown and described.

DESCRIPTION

FIG. 1 is a perspective view of the bottle;

FIG. 2 is a rear elevational view of the bottle;

FIG. 3 is a top plan view of the bottle;

FIG. 4 is a front elevational view opposite to that of FIG. 2;

FIG. 5 is a side elevational view of the bottle, the view from

the opposite side being a mirror image thereof;

FIG. 6 is a bottom plan view of the bottle;

FIG. 7 is a top plan view, similar to that of FIG. 3, but showing a modified embodiment of the bottle in accordance with the invention;

FIG. 8 is a fragmentary side elevational view of FIG. 7, it being understood that the remaining portions of the side are the same as shown in FIG. 5 and that the opposite side is a mirror image of the embodiment shown in FIG. 5;

FIG. 9 is a fragmentary front elevational view of FIG. 7, it being understood that the remaining portions of the front are the same as shown in FIG. 4 and that the rear and bottom views are the same as FIGS. 2 and 6;

FIG. 10 is a top plan view, similar to those of FIGS. 3 and 7, but showing a second modified embodiment of the bottle in accordance with the invention;

FIG. 11 is a fragmentary side elevational view of FIG. 10, it being understood that the remaining portions of the side are the same as shown the reverse image of FIG. 5 and that the opposite side is that shown in FIG. 8; and,

FIG. 12 is a fragmentary front elevational view of FIG. 10, it being understood that the remaining portions of the front are the same as shown in FIG. 4 and that the rear and bottom views are the same as FIGS. 2 and 6.
